SADDLE CONSTRUCTION

Roland W. Faulhaber, Monroeville, Ohio, assignor
to The Faulhaber Company, Monroeville, Ohio,
a corporation of Ohio

Application January 27, 1941, Serial No. 376,139

13 Claims. (Cl. 155—5.23)

This invention relates to saddles for bicycles, velocipedes, and the like.

The principal object of this invention is to house and conceal the reach and spring supporting mechanism and the connections between the reach and springs in a saddle of this type, so as to make the saddle safer and improve the appearance. Other objects are to provide an improved means for securing a flexible covering material and cushion to the seat base of a cycle saddle; to improve the appearance and enhance the safety of the saddle, while simplifying and reducing the cost of the spring supporting mechanism for the saddle; and to house and conceal the supporting mechanism of the saddle by a cover plate carried by the seat without interfering with the freedom of action of the spring suspension mechanism or with the adjustment of a saddle post. Other objects and advantages of the invention will appear in the following description of preferred embodiments of the invention.

In the accompanying drawings:

Figure 1 is a perspective view of a saddle constructed in accordance with this invention.

Figure 2 is a longitudinal section through the saddle shown in Figure 1.

Figure 3 is a longitudinal section through a slightly modified form of saddle.

Figure 4 is an enlarged detail sectional view taken on the line 4—4 of Figure 2.

Figure 5 is a detail sectional view taken on the line 5—5 of Figure 3.

Figure 6 is a sectional view taken on the line 6—6 of Figure 5.

Figure 7 is a longitudinal section through another embodiment of the invention.

Figure 8 is a bottom plan view of the saddle shown in Figure 7.

Figure 9 is a detail sectional view taken on the line 9—9 of Figure 7.

Figure 10 is a top plan view of the reach embodied in the saddle shown in Figure 7.

Figure 11 is a detail elevation of the saddle post and clamp for the saddle shown in Figure 7, and

Figure 12 is an enlarged detail sectional view taken on the line 12—12 of Figure 8.

Referring to the drawings, the saddle illustrated in Figures 1 and 2 includes a seat, reach and supporting springs of the general type illustrated in my copending application Serial No. 254,664, filed February 4, 1939, which became Patent No. 2,279,817 on April 14, 1942. The seat includes a sheet metal base member 10 formed to shape and provided with a depending peripheral flange 11. The base is shaped to provide a

5 relatively wide rear portion and a relatively narrow nose portion, as is customary. The depending flange 11 is flared outwardly and rearwardly around the rear portion of the seat to give the saddle a streamlined appearance, as illustrated in my said copending application.

A reach 12 is suitably connected to the nose portion of the base member 10, as by a pivotal connection illustrated at 13. At the rear end 10 of the reach carries a cross member 14, on the opposite ends of which are supported coil springs 15. The upper ends of the coil springs are connected to the base member 10 by connecting pieces 16 shown secured to the base member 10. 15 In the embodiment illustrated a saddle post 17 is riveted or otherwise permanently secured to the reach member 12.

A cushion 18, which may be of sponge rubber or any suitable cushioning material, is supported on the upper side of the base member 10. A flexible covering sheet 19 of imitation leather or other suitable material is disposed over the cushion 18 and is extended down around the flange 11 and turned in about the lower edge of the flange.

20 A bottom cover plate 20 is arranged to conceal and prevent contact with the reach and spring mechanism and the connections between the same and the seat base. The bottom cover plate 20 is provided with an upstanding peripheral flange 21 shaped to conform with and to fit within the depending flange 11 of the base member 10, with the inturned edge of the flexible covering material 19 gripped between the flanges 11 and 21 around the entire edge of the flange 11. The cover plate 20 is also formed with an aperture 22 through which the saddle post 17 extends, the aperture 22 being formed of such size and shape as to permit the lateral and fore and aft movements of the saddle post which occur as a result 25 of the compression of the springs 15 in transmitting loads from the seat to the saddle post.

40 The bottom cover plate 20 may be secured to the seat in any suitable manner. The novel securing means illustrated in the drawings is preferred for its simplicity, cheapness and ease of assembly. As shown the flange 21 of the cover plate 20 is provided with an extension at the nose portion of the saddle which is turned outwardly, as shown in Figures 5 and 6, to form an abutting shoulder 23. Similarly the flange 11 of the seat base 10 is formed with an extension turned inwardly to form an abutting shoulder 24 mating with the shoulder 23. The circumferential extent of these shoulders may be short as illustrated in Figure 5, the edges of the flanges 11 and 21 being

simply left in their raw condition throughout the remainder of their circumferences. After the seat has had the cushion 18 and the flexible cover 19 assembled over it, and the springs 15 and reach 12 secured in position on its lower side, the free edge of the covering material 19 is turned inwardly over the flange 11. The bottom cover plate 20 is then slipped over the seat post 17 and the flange 21 of the cover plate is forced into the flange 11, gripping the inturned edge of the covering material and pulling it tight about the entire periphery of the base member 10. The flanges 11 and 21 yield sufficiently to permit the mating shoulders 23 and 24 at the nose portion to be forced past each other into interlocking relationship as illustrated in Figure 6.

After the bottom cover member 20 has been pressed into position it is additionally secured at one or more points at the rear portion of the saddle. As illustrated this may be effected by spot welding a nut 25 to the inner surface of the flange 21 and threading a bolt 26, carrying an ornament 27, through aligned holes in the flanges 11 and 21 into the nut 25. Openings are also provided in the flexible covering material 19 to permit the passage of the bolt 26. The base 10 and bottom cover 20 are thus secured together at two points; one at the abutments 23 and 24 at the front end of the saddle, and the other, by the bolt 26, at the rear end of the saddle. The flange 21 between these points is formed to fit closely within the flange 11 of the seat base 10 and to extend into snug engagement with the inwardly curved shoulder portions 28 at the sides of the seat base 10 as illustrated in Figure 4. Thus pivoting or rocking of the seat base 10 and the cover member 20 with respect to each other about their two points of connection is prevented by the wedging of the flange 21 into the inwardly curved shoulders 28 on both sides of the seat.

A slightly modified construction is illustrated in Figure 3 in which is shown a somewhat differently shaped seat base 30 and a different type of reach and supporting spring construction. As shown in Figure 3 the reach 32 is of the type illustrated in my copending application Serial No. 185,940, filed January 20, 1938, embodying two parallel lengths of strap iron between which is clamped a serrated eye 36 of a saddle post 37 by means of a bolt 38. The forward end of the reach may be connected to the seat by a nose coil or the like 33. The rear end of the reach is extended laterally to form spring supports 34 on which are mounted a pair of coil springs 35 having their upper ends riveted or otherwise suitably secured to the seat base 30. The bottom cover member 40 is secured in position and acts to clamp the flexible covering of the seat in the same manner as described in connection with Figures 1 and 2. The bottom cover member is provided with an aperture 42 of a size and shape to permit access to the bolt 38 for adjusting the saddle post 37 and to permit the necessary working of the saddle post 37 in any adjusted position without contact with the cover member 40.

A somewhat different embodiment of this invention is illustrated in Figures 7-12, inclusive. As shown in Figure 7 the saddle includes a drawn sheet metal base member 50 on which is positioned a cushion 51 covered by a sheet of flexible covering material 52. A reach 53, which as illustrated comprises a single sheet metal stamping, is formed at its rear end with laterally

extending platforms 54 supporting spaced coil springs 55. Desirably the platforms 54 may be provided with flanges 56 defining the spring seats and the bottom convolutions of the spring 55 may be secured to the platforms 54 in any suitable manner. The upper ends of the springs 55 may likewise be connected to the underside of the base 50 in any suitable manner as by plates 57.

10 The forward end of the reach 53 is likewise provided with laterally projecting spring platforms 58 which may be formed in the same manner as the platforms 54 to support spaced coil springs 59. The upper ends of the springs are 15 likewise secured to the base member 50 in any desired manner as by rivets 60.

The intermediate portion of the reach comprises downwardly extending substantially parallel wings 61. As shown the reach is stamped from a single flat sheet of metal from which the wings 61 are bent downwardly but it will be understood that the reach may also be formed of separate members connected to the spring supports in any suitable way. In this embodiment a clamp 62 is provided to connect the reach to a saddle post 63 having its upper end 64 disposed substantially horizontally. The clamp 62 comprises a single piece of sheet metal bent to form a partially closed tubular portion 65 proportioned to fit around and grip the end 64 of the saddle post, and downwardly extending side pieces 66 arranged to fit between the wing members 61 of the reach. Cooperating serrations 68 are formed on the outer surfaces of the side members 66 of the clamp and on the inner surfaces of the wings 61 of the reach, and these members are provided with aligned apertures to receive a clamping bolt 67. With the horizontal arm 64 of the saddle positioned in the tubular portion 65 of the clamp the bolt 67 may be drawn up to firmly grip the saddle post in the tubular portion 65 and to press the wings 61 tightly against the side member 66 so that the serrations 68 hold the clamp firmly against turning in any desired position.

40 A bottom cover plate 70 is drawn from a single piece of sheet metal and is arranged to fit over and conceal the reach and spring mechanism and to secure the covering material 52 to the base 50. In the embodiment illustrated in Figures 7 to 12 the bottom cover plate 70 is formed with an outwardly and downwardly turned flange 71 extending around substantially the entire periphery of the cover 70 except around the forward end of the nose portion of the saddle where the flange is turned substantially horizontally as shown at 72 in Figures 7 and 12. Around the nose portion the base member 50 is formed with a substantially horizontal inwardly projecting flange 73 and an inwardly extending projection 74 spaced above the flange 73. The flange 73 and projection 74 extend only around the nose as shown in Figure 8 and desirably the remainder of the peripheral edge of the base member 50 is left unflanged.

50 As in the embodiments previously described the covering material 52 is stretched tightly over the cushion and base member 50 and has its free edge turned in around the periphery of the base member 50. After the springs and reach are assembled the cover 70 is pressed into position. The flange 71 of the cover 70 is shaped to fit closely within the edge of the base member 50 so that it grips and clamps the free edge 75 of the covering material 52 between the base

50 and the flange 51. At the nose portion the horizontally turned flange 72 of the cover 70 fits between the flange 73 and projection 74 on the base 50 with the free edge of the covering material interposed between the flange 72 and the base 50 as illustrated in Figure 12. In assembling the saddle it is apparent that the flange 72 may first be slipped into position over the flange 73, after which the entire cover 70 may simply be pressed into the edge of the base member 50, clamping the flexible covering material 52 throughout its periphery. Any suitable means may be employed to additionally secure the cover member 70 in position, such as one or more bolts 75 shown in Figures 7 and 8. Additional securing means may be employed if desired to prevent the possibility of the cover rocking about its longitudinal center line with respect to the base, or the fit of the side portions of the flange 71 in the edge of the base member 50 may be relied upon to prevent such rocking as in the embodiments previously described.

The cover member 70 is provided with a slot 76 which is of sufficient width and length to permit the wings 61 of the reach 53 to pass therethrough when the saddle is being assembled and to permit the removal and adjustment of the saddle post 63. The cover is preferably formed as shown in Figure 7 so that the lower portions of the wings 61 and the clamping bolt 67 are disposed outside of the cover 70 while the major portion of the reach and the springs are housed between the cover and base member 50.

In this embodiment of my invention the base 50 is supported from the reach by four springs 55 and 59 which provide a much better cushioning action against shocks in all directions than the customary spring arrangement for saddles. This arrangement of springs, which would be unsightly and dangerous to the user if exposed, may be employed because the spring mechanism is housed and concealed by the cover member 70. In Figures 7 and 8 I have also illustrated the cover 70 as formed with streamlined flutes or steps 77 to illustrate how the bottom cover member may be utilized to ornament and improve the appearance of the saddle.

The bottom cover members 20, 40, and 70 may be shaped and colored to harmonize with the main portion of the seat, and function not only to tighten and secure the flexible covering material in place over the seat base, but also to conceal and prevent contact with the seat supporting mechanism. Thus relatively rough, unfinished parts may be employed for the reach and spring supporting mechanism, and painting of these members and of the inner surfaces of the seat base and bottom cover member may be dispensed with without impairing the appearance. The housing of the reach and spring mechanism is an important consideration from the standpoint of safety since it prevents the clothing or hands of the user from being caught, scratched or torn from accidental contact with these elements. The bottom cover member may be spaced below the reach only a sufficient distance to avoid contact between the reach and the bottom cover member when the load is removed from the seat in normal use.

In the type of construction in which the saddle post is permanently fixed in position as illustrated in Figures 1 and 2 the aperture 22 in the bottom cover member may be made relatively small and with a relatively close fit about the saddle post. In the type of saddle such as illus-

trated in Figure 3 in which an adjustable connection is provided between the reach and the saddle post it is only necessary to make the aperture in the bottom cover member enough larger to permit access to the adjusting means and to permit the movement of the saddle post in different directions in any adjusted position. In the type of saddle illustrated in Figures 7 to 12 embodying a somewhat more complex adjustable connection it is preferred to project the reach and the clamping bolt outside the cover member to facilitate the use of the adjustable connection.

It will be understood that any desired design and arrangement of reach and spring suspension may be employed, and that the several features of the invention may be used independently as well as in combination. The terms "spring" and "springs" are used in the claims, not to indicate the specific forms of springs illustrated but to comprehend all equivalent resilient means. Other modifications and rearrangements of the parts may be resorted to without departing from the scope of the invention as defined in the following claims.

I claim:

1. A saddle for cycles comprising a seat, a post connected to said seat for mounting the saddle on a cycle, the connections between said seat and post including a spring to cushion the seat with respect to the cycle, and a bottom cover plate secured to said seat and depending therefrom, said cover plate housing and concealing the connections between said post and said seat, and said cover plate being formed with an opening through which said post extends, said opening being of sufficient size to permit unrestrained movement of said post during the cushioning action of said spring.

2. A saddle for cycles comprising a seat, a reach, means, including springs, connecting said reach to said seat, a post connected to said reach and extending downwardly therefrom for mounting the saddle on a cycle, and a bottom cover plate secured to said seat and extending below and around said springs and at least the major portion of said reach, said cover plate being formed with an opening through which said post extends and said cover plate and said seat defining a substantially closed space housing said reach and said springs.

3. A saddle for cycles comprising a sheet metal seat base having a depending peripheral flange, a cover of flexible material disposed over said base and turned in over said flange, a bottom cover plate having an upwardly extending peripheral flange fitting within the depending flange of said base, the in-turned edge of said flexible cover being gripped between said flanges, and supporting springs for said saddle connected to said seat base and disposed between the same and said bottom cover plate.

4. A saddle for cycles comprising a sheet metal seat base having an outwardly curved depending peripheral flange, a bottom cover plate spaced from said base and having an upwardly extending peripheral flange fitting within the depending flange of said base, means securing said bottom cover plate to said base at the front and at the rear of said base, the flange of said bottom cover extending upwardly along the side portions into close fitting relationship with the outwardly curved portions of the flange of said base so as to prevent relative movement of said

base and said bottom cover about said securing means.

5. A saddle for cycles comprising a sheet metal seat base having a depending peripheral flange, a cover of flexible material disposed over said base and turned in over said flange, a bottom cover plate having an upwardly extending peripheral flange fitting within the depending flange of said base, the in-turned edge of said flexible cover being gripped between said flanges, and supporting springs for said saddle connected to said seat base and disposed between the same and said bottom cover plate, and a saddle post connected to said springs and extending through an opening formed in said cover plate.

6. A saddle for cycles comprising a sheet metal seat base having an outwardly curved depending peripheral flange, a flexible covering over said base turned in around said flange, a bottom cover plate spaced from said base and having an upwardly extending peripheral flange fitting within the depending flange of said base with the flexible covering gripped between said flanges, means securing said bottom cover plate to said base at the front and at the rear of said base, the flange of said bottom cover extending upwardly along the side portions into close fitting relationship with the outwardly curved portions of the flange of said base so as to prevent relative movement of said base and said bottom cover about said securing means.

7. A saddle for cycles comprising a sheet metal seat base formed with a relatively narrow nose portion and a widened rear portion and a depending peripheral flange, said flange being flared outwardly and rearwardly around the widened rear portion, a bottom cover plate secured to said seat base and having its central portion spaced therebelow, said cover plate having an upwardly extending flange flared outwardly and rearwardly around the rear portion of the seat and substantially matching the flange on said seat base.

8. A saddle for cycles comprising a sheet metal seat base formed with a relatively narrow nose portion and a widened rear portion and a depending peripheral flange, said flange being flared outwardly and rearwardly around the widened rear portion, a bottom cover plate secured to said seat base and having its central portion spaced therebelow, said cover plate having an upwardly extending flange flared outwardly and rearwardly around the rear portion of the seat and substantially matching the flange on said seat base and spring supporting means for said seat housed between said base and said cover plate and having a saddle post projecting out thru an aperture in said cover plate.

9. A saddle for cycles comprising a seat, a reach, springs mounted on said reach and connected to said seat, means extending downwardly from said reach for mounting the saddle on a cycle, and a bottom cover plate secured to said seat and extending below and around said springs and said reach, said cover plate being

formed with an opening thru which said means extends and said cover plate and said seat defining a substantially closed space housing said springs.

5 10. A saddle for cycles comprising a seat, a reach, means including springs connecting said reach to said seat, said reach being formed with downwardly extending members cooperating with a clamp for securing said reach to a seat post and a bottom cover plate secured to said seat and extending below and around said springs and the major portion of said reach, said cover plate being formed with an opening thru which said downwardly extending members of the reach extend and said cover plate and said seat defining substantially a closed space housing said springs.

11. A saddle for cycles comprising a seat base, a reach, means including springs connecting said reach to said seat base, a saddle post, clamping means including a screw threaded member carried by said reach adapted to be manipulated to secure said reach to said saddle post or to release the same therefrom, and a cover connected to and extending below said seat base and around said springs and the major portion of said reach, said cover being formed with an opening through which a portion of said reach projects, said cover and base defining a substantially closed space housing and concealing said springs, said screw threaded member being disposed outside of said space in the normal unloaded condition of said springs, said opening being of sufficient size to permit movement of said screw threaded member into said space during the cushioning action of said springs.

12. A saddle for cycles comprising a seat base, a reach, means connecting said reach to said seat base including a plurality of coil springs positioned between said reach and said seat base with their axes disposed substantially vertically, at least one of said coil springs being connected to the rear end of said reach and at least one of said coil springs being connected to the forward end of said reach, and a cover secured to and extending below said seat base and around said springs and said reach, said cover and base defining a substantially closed space housing and concealing said springs and said cover being formed with an opening permitting said reach to be connected to a cycle.

13. A saddle for cycles comprising a seat base, a reach, a plurality of coil springs positioned between said reach and said seat base with their axes disposed substantially vertically connecting said reach to said seat base, at least one of said springs being connected to the forward end of said reach and to said seat base, and a cover secured to and extending below said seat base and around said springs and said reach, said cover and base defining a substantially closed space housing and concealing said springs and said cover being formed with an opening permitting said reach to be connected to a cycle.

ROLAND W. FAULHABER.
